Inventor

Edward Asa Burpee

UNITED STATES PATENT OFFICE.

EDWARD ASA BURPEE, OF RENTON, WASHINGTON.

TOOL FOR RESTORING SWAGE-BITS.

1,378,006.

Specification of Letters Patent. Patented May 17, 1921.

Application filed January 24, 1920. Serial No. 353,736.

To all whom it may concern:

Be it known that I, EDWARD ASA BURPEE, a citizen of the United States, residing at Renton, in the county of King and State of Washington, have invented a new and useful Tool for Restoring a Swage-Bit to Good Condition After the Lips Thereof Have Been Bent and Otherwise Injured, of which the following is a specification.

10 My invention relates to a tool employed for restoring the swage-bit to good working condition after the lips thereof have been bent and otherwise impaired by striking a nail or other hard substance in wood, and 15 the objects of my invention are, first, to make the bent and injured lips of such bit straight and renew the original utility of said bit, and second, to save the money required to buy a new bit.

20 I attain these objects by the mechanism illustrated in the accompanying drawing, in which—

Figure 1 is an independent view of said invention, and Fig. 2 is the boring part of a 25 swage-bit, one of whose lips has been bent and impaired by striking a nail or other hard substance, together with the position and angle of said invented tool for use in straightening and restoring said bent lip and 30 bit to good condition and gage.

As the invention consists of but one part, the numbers of the figures only are shown in the several views.

Fig. 1 is a hard metal bar, preferably 35 steel, curved and concave at one end behind which and through which bar is an elliptical hole fitting loosely, when in use, over the screw and point of said bit making said

curved and concave end adjustable to either of said lips both when the latter are bent 40 and in normal position, and which bar thence tapers to its other end and is of suitable dimensions for convenient use.

Fig. 2 is the boring part of a swage-bit, showing one of its lips bent, and the invented tool adjusted to the proper position and angle for use to straighten said bent lip and restore said bit to good condition and gage.

A person with a hammer may use the tool 50 for the purpose stated. In the manufacture of said tool, its size should correspond to the size of the bit.

It often occurs that the lips of a swage-bit, after much usage, will lose their keen 55 cutting quality with more or less loss of gage or clearance, in which case the use of said tool and a whet-stone will restore this lost quality, when without such tool the bit would remain worthless.

Having thus described and illustrated my invention, I claim:

A tool for use in restoring to good working condition a swage-bit whose lips or lip have been bent and otherwise impaired, said 65 tool being a hard metal bar curved and concave at one end thereof, behind which end and through which bar is an elliptical hole that fits loosely over the screw and point of said bit making said curved and concave end 70 adjustable to said lips both when the latter are bent and in normal position, and which bar thence tapers to its other end and is of suitable dimensions for convenient use, substantially as described and shown.

EDWARD ASA BURPEE.
